(57) CLAIM

The ornamental designs for vehicle front headlamp daytime running lights, as shown and described.

DESCRIPTION

FIG. 1 is a frontside perspective view of the vehicle front headlamp daytime running lights shown equipped on a passenger-side of a vehicle and on a driver-side of the vehicle;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rearside perspective view thereof; and,

FIG. 8 is a rear view thereof.

The broken lines in the drawings indicate a boundary residing between claimed and unclaimed portions. The broken lines form no part of the claimed designs. The claimed designs are indicated by the encircled portions of the daytime running lights, while the relatively lighter portions are environment and form no part of the claimed designs.
